US00D772232S

(12) **United States Design Patent** (10) **Patent No.:** **US D772,232 S**
Cho (45) **Date of Patent:** **** Nov. 22, 2016**

(54) **MEMORY CARD**

(71) Applicant: **SAMSUNG ELECTRONICS CO., LTD.**, Suwon-si (KR)

(72) Inventor: **Hee-Chang Cho**, Seoul (KR)

(73) Assignee: **SAMSUNG ELECTRONICS CO., LTD.**, Suwon-si (KR)

(**) Term: **15 Years**

(21) Appl. No.: **29/546,125**

(22) Filed: **Nov. 19, 2015**

(30) **Foreign Application Priority Data**

Nov. 12, 2015 (KR) 30-2015-0057077

(51) **LOC (10) Cl.** **14-02**
